TOY CONSTRUCTION ELEMENT

Jan de Swart, Los Angeles, Calif., assignor, by
mesne assignments, to Illinois Tool Works, Chi-
cago, Ill., a corporation of Illinois

Application June 3, 1947, Serial No. 752,104

5 Claims. (Cl. 46—17)

1

This invention is concerned with improvements in toy constructions of the type in which an assortment of interfitting elements of varying kinds are adapted to be manually assembled, without the use of bolts or similar fastening elements, into structures and mechanisms of widely varying sizes and types.

It is an object of the invention to provide an improved toy construction of the type described which is particularly adapted to be manufactured of plastic materials, which comprises a small number of basic elements, which can be readily furnished to the user with as many duplicate parts as desired and which is so constructed that the user can combine the parts to construct an enormous number of rigid and movable structures.

It is another object of the invention to provide a toy construction of the type described which comprises five basic elements or parts, all of which are readily formed in an economical manner by molding or extruding plastic materials, which parts may be duplicated as desired, which may be furnished in various sizes and colors, and at least one of which may be divided into a large number of sub-elements.

A further object of the invention is to provide in a toy construction of the type described a wheel member and a cooperating strip member having an axle for receiving the wheel member whereby the wheel member may be mounted for rotation on the axle and wherein means is provided on the axle and the wheel for releasably retaining the wheel member in rotatable relation thereto.

A still further object of the invention is to provide, in a toy construction of the type described, a member having an apertured strip portion and provided with socket forming an axle forming laterally projecting end formations, and which is adapted to be sub-divided to provide a number of sub-elements for cooperation with other toy elements in providing a versatile set of toy construction elements capable of assembly into many different real and simulated devices.

These and other objects of the invention will be apparent from a description of the preferred embodiments thereof which are shown by way of illustration in the accompanying drawings, wherein:

Fig. 1 is a perspective view of a wheeled toy constructed with a plurality of toy elements which embody the principles of the invention;

Fig. 2 is an elevation of a strip member forming one of the basic elements of the toy;

2

Fig. 3 is a plan view of the strip member;

Fig. 4 is a plan view of a wheel member form-

ing one of the basic elements of the toy;

Fig. 5 is a section on the line 5—5 of Fig. 4;

Fig. 6 is an elevation of a rod forming another of the basic elements of the toy;

Fig. 7 is a section on the line 7—7 of Fig. 6;

Fig. 8 is a partial plan view of a plate mem-
ber forming another basic element of the toy;

Fig. 9 is an elevation of a split tube member
forming still another basic element of the toy;

Fig. 10 is a section on the line 10—10 of Fig. 9;

Figs. 11 and 12 are an elevation and plan view,
respectively, of a sub-element formed by modify-

15 ing the strip member shown in Figs. 2 and 3;

Figs. 13 and 14 are an elevation and plan view,
respectively, of a socket and axle member which
corresponds to the end formation of the strip
member shown in Figs. 2 and 3;

20 Figs. 15 and 16 are an elevation and plan view,
respectively, of a sub-element corresponding to a
portion of the end formation and a portion of the
strip member shown in Figs. 11 and 12;

Figs. 17 and 18 are an elevation and plan view,
25 respectively, of a flat strip member which cor-
responds to the central portion of the strip mem-
ber shown in Figs. 2 and 3;

Figs. 19 and 20 are an end elevation and plan
view, respectively, of a socket and pin member
30 which corresponds to a portion of the end for-
mation on the strip member shown in Figs. 2
and 3;

Figs. 21 and 22 are an elevation and plan view,
35 respectively, of a sub-element corresponding to a
portion of the end formation of the strip member
shown in Figs. 2 and 3;

Figs. 23 and 24 are an elevation and plan view,
40 respectively, of a sub-element corresponding to a
portion of the sub-element shown in Figs. 21
and 22; and

Figs. 25 and 26 are an elevation and plan view,
45 respectively, of a sub-element corresponding to a
portion of the end formation of the strip member
shown in Figs. 2 and 3.

In Fig. 1 there is illustrated an assemblage of
toy construction elements which simulates a
wheeled vehicle provided with hoisting mecha-
nism. The assemblage is typical of a number of
arrangements which it is possible to construct
50 with a plurality of the basic elements and sub-
elements which constitute the invention. The
number of assemblies and the types of construc-
tion possible with the elements provided are lim-
ited only by the imagination and ingenuity of
55 the user.

3

In Figs. 2 and 3 of the drawings, there is illustrated a strip member 10 which constitutes one of the basic elements of the invention. The member 10 consists of a relatively flat narrow strip portion 11 provided with spaced apertures 12 and end formations 13. The strip portion 11 may be made solid, or provided with recesses, effecting a saving of material, or with reinforcing ribs, providing increased strength. The end formations 13 include a tubular portion 14 projecting upwardly from the top face of the strip portion 11. The tubular portion 14 is provided with a socket forming bore 17 which is preferably the same diameter as the apertures 12 in the strip portion 11. Projecting from the opposite face of the strip portion 11 is a relatively short pin 18 which is of a cross-sectional diameter which permits it to be loosely positioned in the socket 17 or in an aperture 12. The pin 18 and the socket 17 are adapted to cooperate to permit a plurality of the strip members 10 to be positioned in connected relation with the members either superimposed on each other or extended at any desired angle relative to each other. Each end formation 13 is also provided with relatively short laterally extending pin members 19 which are duplicates of each other but extend in opposite directions edgewise of the strip member 10 in substantially the same plane as the strip portion 11. Each pin member 19 is slotted on the end at 20 and provided with a circumferential shoulder 21 near the free end thereof. The pin members 19 are of a cross-sectional diameter slightly less than the diameter of the apertures 12 in the strip portion 11 and the shoulder 21 is of slightly greater diameter. The end of the pins 19 may be resiliently compressed by means of the slot 20 to permit the shoulder 21 to pass through an aperture 12.

In Figs. 4 and 5 a wheel 22 is illustrated which constitutes another basic element. The wheel 22 is designed to cooperate with the pin member 19 of the strip member 10 and is provided with a central aperture or bore 23 which is of slightly larger diameter than the cross-sectional diameter of the pin member 19 but which is of a smaller diameter than the diameter of the shoulder 21 on the pin 19 so that the wheel may be forced over the shoulder 21 and into rotatable relation with the pin. The pin 19 forms an axle for the wheel 22 while the shoulder 21 prevents removal of the wheel 22 except by the application of sufficient force axially of the pin 19 to constrict the split ends of the pin 19 and permit the wheel to be forced outwardly over the shoulder 21. The wheel 22 is provided with projecting hub or shoulder portions 24 and 25 which extend outwardly somewhat of the face of the wheel on each side. The wheel 22 is preferably provided with an annular recess 26 which effects a saving of material without any appreciable reduction in strength. Circumferentially spaced apertures 27 are also provided around the outer edge of the wheel. The apertures 27 are preferably the same size as the central bore 23. The member 22 provides a basic wheel element for rotatably and detachably mounting on the pins 19. The central bore 23 and the annular spaced apertures 27 will loosely receive the pin 18 on the member 10 providing a loose connection between the wheel 22 and member 10, if desired.

Another basic element of the toy is illustrated in Figs. 6 and 7. This element comprises a solid rod member 28 having a cross-sectional diameter somewhat less than the diameter of the

4

holes 12, 17 and 23 in the elements 10 and 22. The rod 28 may be furnished in any desired length or in a number of different lengths for use in the toy.

A flat plate-like member 29 is illustrated in Fig. 8 which constitutes the fourth basic element of the toy. The plate 29 may be any desired size or it may be provided in any number of different sizes. In the construction shown in Fig. 1 the plate 29 is approximately square and is used to form the base of the vehicle. Plate members may be provided having other shapes. In the illustrated form plate 29 is provided with a series of spaced holes 30 adjacent the outer edges. The corner holes 30 are preferably spaced from each other a distance corresponding to the space between the pins 18 on the strip member 10. The holes 30 are of a diameter sufficient to loosely receive the pins 18. Any other arrangement of the holes 30 for construction of special assemblies may, of course, be provided.

The fifth basic element of the toy is illustrated in Figs. 9 and 10 and comprises a tubular member 31 having a longitudinal slot 32. The tubular member 31 is preferably formed with an outside diameter slightly larger than the diameter of the holes 12 and 17 of the strip member 10. The slot 32 permits the tubular member 31 to be resiliently constricted so that it may be inserted in the holes 17 or 12 and adjustably held therein. This permits the assemblage of the elements 10, 22 and 29 in various rigid and adjustable relationships.

The elements provided by the basic members, namely, the strip member 10, the wheel 22, the solid rod 28, the plate 29 and the slotted tube 31 may be supplemented by sub-elements which may be readily formed to correspond to portions of the basic element 10. Such sub-elements are illustrated in Figs. 11 to 26.

In Figs. 11 and 12 the sub-element 33 consists of a strip portion 34 which corresponds to the strip portion 11 of the element 10 and end formations 35 which are provided with a laterally extending tubular member 36 having a socket 37 and an oppositely extending pin member 38. The end formations 35 correspond to the members 14 and 18 of the element 10. The strip forming portion 34 is provided with spaced apertures 39 of the same size as holes 12 in member 10.

The sub-element 40 which is illustrated in Figs. 13 and 14 corresponds to the end formation 13 of basic member 10. Element 40 consists of a tubular portion 41 having socket 42, a pin 43 extending in the opposite direction and laterally extending axle forming members 44. The axle forming members 44 are slotted at 45 and provided with an annular shoulder 46 adjacent the free end.

The sub-element 47 which is illustrated in Figs. 15 and 16 corresponds to a portion of the end of the basic member 10. Element 47 comprises a tubular portion 48 having a socket 49, a pin 50 extending in the opposite direction and a laterally extending relatively short strip 51. The strip 51 is provided with an aperture 52 preferably of the same diameter as aperture 12 in element 10.

The sub-element 53 which is illustrated in Figs. 17 and 18 corresponds to a portion of the strip 11 of basic member 10. Element 53 comprises a flat relatively narrow strip having three spaced apertures 54 which are preferably of the same diameter as apertures 12 of the strip member 10. Other

sub-elements of this type may be provided of different lengths and with a different number of holes to further increase the variety of parts constituting the toy.

A further sub-element 55 which is illustrated in Figs. 19 and 20 corresponds to a portion of the end of basic element 10. The sub-element 55 comprises a tubular member 56 having a socket 57 and a pin 58 extending in the opposite direction.

Another sub-element 59 which is illustrated in Figs. 21 and 22 corresponds to a portion of the end of basic element 10. This sub-element comprises a tubular center portion 60 having a bore 61 and oppositely extending axle forming pins 62. Each of the pins 62 is slotted at 63 on its end and is provided with a shoulder 64 adjacent the end. The pins 62 form axles for wheel member 22.

Another sub-element 65 which is illustrated in Figs. 23 and 24 corresponds to a portion of the end of base element 10. This sub-element comprises a tubular portion 66 having central bore 67 and a laterally extending axle forming pin 68 having a slotted end at 69 and a wheel retaining shoulder 70. This sub-element forms a universal joint connection for use with the wheel member 22.

A final sub-element 71 which is illustrated in Figs. 25 and 26 also corresponds to a portion of the end of basic element 10. This sub-element forms in effect a washer or spacer member having a central bore 72 which may be the same cross-sectional diameter as the bore 17 in basic element 10.

While the elements illustrated are sufficient to provide all the parts needed to adapt the toy for construction of an enormous number of real and simulated articles or devices, it will be understood that other elements may be used with the illustrated elements to further increase the usefulness of the toy.

I claim:

1. A toy construction element comprising a relatively flat elongate bar having integral end formations, said bar being provided with spaced bores between said end formations, each of said end formations comprising a laterally extending open-ended tubular portion provided with an axial bore, a short pin extending in a direction opposite to the tubular portion and laterally directed opposed axle forming pin members, each of said pin members having a slotted end and provided with a wheel retaining peripheral shoulder spaced inwardly of said end.

2. A toy construction element comprising an intermediate flat bar having integral end formations, said bar being provided with a plurality of

spaced bores intermediate its ends and each of said end formations being provided with an integral tubular portion having a socket forming axial bore of the same size as the bores in said bar.

3. A toy construction element comprising a relatively narrow flat bar portion and an integral end formation, said end formation comprising a socket forming tubular portion extending laterally from one flat face of said bar portion and a relatively short pin member extending laterally from the opposite flat face of said bar portion.

4. A toy construction element comprising an elongate relatively flat bar portion and an integral end formation, said bar portion having spaced bores, said end formation comprising a tubular portion provided with an axial bore, a short pin extending in the opposite direction to the tubular portion and a laterally directed axle forming member, said axle member being slotted at the end thereof and having a wheel retaining shoulder adjacent the end thereof, said tubular portion, pin and axle members extending radially of the longitudinal axis of said bar portion.

5. A one-piece toy construction element comprising a relatively narrow flat bar portion and an integral end formation, said end formation comprising a socket forming tubular portion extending from one flat face of said bar portion, a relatively short pin member extending from the opposite flat face of said bar portion, and a laterally extending axle forming member having a split end and a wheel retaining annular shoulder.
